Fig. 5

FIGURE 1 is a front perspective view of an electric motor driven centrifugal pump embodying the invention and showing the liquid end of the pump, the top of the pump, and left side of the pump;

FIGURE 2 is a bottom perspective view of the pump shown in FIGURE 1, and showing the bottom of the pump, the electric inlet end of the pump, and the right side of the pump;

FIGURE 3 is a reduced scale top plan view of the pump shown in FIGURES 1 and 2;

FIGURES 4 and 5 are views similar to FIGURES 1 and 2 showing a modified form of the invention wherein the pump inlet is a short pipe nipple instead of the hooded,

bottom opening, inlet of the embodiment of FIGURES 1 and 2.

I claim:

The ornamental design for an electric motor driven centrifugal pump, as shown and described.
